UNITED STATES PATENT OFFICE.

FRANK E. ALLEN, OF ST. CLAIR, MICHIGAN, ASSIGNOR OF ONE-HALF TO WILLIAM D. THOMPSON, OF PORT HURON, MICHIGAN.

TOURIST'S AUTO CAMPING OUTFIT.

Application filed April 25, 1925. Serial No. 25,888.

This invention relates to camping equipment, and particularly to a combined foldable tent and supporting structure therefor, a foldable table, cot, and cabinet.

5 The general object of the invention is to provide a camping equipment of this kind which includes a box or case formed in two hinged sections and opening out like a dress suit case and closing like a dress suit case, the tent supporting structure, table, cot and other parts being adapted to fold up within the box or case, this case being adapted to be carried upon the running board of an automobile or on the rear of the running board. 10 15 A further object is to provide a tourist camping outfit of this character including a table suitable for two or four people, a cabinet for dishes and provisions, a cot for two people also, a tent which folds up within 20 in the case and the supporting structure therefor, the case being so constructed as to provide room for foldable cots for two people and for folding chairs for four people.

25 A still further object is to provide a structure of this character which is simple, compact, may be readily unfolded and set up and as readily folded, and in which the tent is formed of sections of canvas supported upon 0 and foldable with the frame, the sections being engaged with each other and with the case by snap fasteners or like means.

Other objects will appear in the course of the following description.

5 My invention is illustrated in the accompanying drawings, wherein:

Figure 1 is a diagrammatic elevation of an automobile showing the case with which my camping outfit is disposed mounted upon 0 the running board of the automobile;

Figure 2 is a side elevation of the case showing the tent supports unfolded from the case and ready for the canvas;

Figure 3 is an elevation of the case and a transverse section of the tent supports;

Figure 4 is a top plan view of the case and the tent supports;

Figure 5 is a fragmentary perspective view of one end of the case and a portion of the 0 tent supports partly folded;

Figure 6 is a vertical section through one of the stringers showing the manner in which the rafter section are folded;

Figure 7 is a fragmentary side elevation

of one of the members 22 showing the manner in which the other member 22 is joined thereto;

Figure 8 is a fragmentary transverse section through the peak of the roof showing the manner in which the two sections are 55 connected to each other at the peak;

Figure 9 is a fragmentary front elevation of the case section Y showing the manner in which the tent supporting sections are folded within the case;

Figure 10 is a top plan view of the tent and a portion of the case;

Figure 11 is a rear elevation of the tent and a portion of the case;

Figure 12 is a front elevation of the tent;

Figure 13 is a side elevation of the tent and case;

Figure 14 is a horizontal section through the section Y of the case showing the table, the cabinets and the bed folded up within 75 the section Y;

Figure 15 is a face view of the lower section of the case, the upper section not being shown, showing the table opened out but the cabinets closed;

Figure 16 is a vertical section on the line 16—16 of Figure 15;

Figure 16^a is a fragmentary elevation of one wall of the box section Y showing the upper end of one of the slots 40;

Figure 17 is a side elevation of the section Y of the case showing the bed opened out;

Figure 18 is a fragmentary top plan view of the forward portion of the bed;

Figure 19 is an elevation of the case showing the bed or cot unfolded.

Referring to the drawings, it will be seen that one portion of the structure comprises a case made after the general fashion of a suit case, this case being formed with two rectangular sections X and Y having their proximate side walls hinged to each other, as at 10, and having latches 11 whereby the two sections of the case may be held closed or whereby the two sections of the case may be held in open position, one above the other. When in use the case rests upon a bottom wall and the side walls of the case and the top wall are provided with snap fastener members 12 and 13 by which the canvas is detachably engaged with the two sections of the case. This case may be fifty-two inches wide, thirty inches high and twelve

inches deep, though any other dimensions may be used, the dimensions given above being the average dimensions.

Hinged to the end walls 14 of the section

- 5 X so as to swing in and out parallel to the top of the section X are the stringers formed of two sections 15 and 16, the section 15 being hinged to the end walls of the case 14, as previously stated, by the hinges 17.
- 10 There are two stringers disposed at each end of the case, and the two sections 15 and 16 of each stringers are hinged to each other, as at 18, so that the stringer may be folded upon itself and then folded into the case.
- 15 Hingedly connected to the stringer sections 15 and 16 are the foldable rafters formed by the sections 19 and 20, the sections 19 being the outside sections and extending from the stringers to the eaves of the roof,
- 20 and the sections 20 being the inner sections and extending from the stringers to the peak of the roof. All of the sections 20 of the stringer sections 16 are connected to a longitudinally extending member 21, while all of the sections 20 connected to the stringer section 15 are connected to a longitudinal member 22. All of the sections 19 of the stringer sections 15 are hinged to a longitudinal member 23 and all of the rafter sections 19
- 25 which are hinged to the stringer sections 16 are connected to a longitudinal member 24. These members 23 and 24 are hinged to each other, as at 25, and the members 21 and 22 are likewise hinged to each other, as at 25.
- 30 When the sections 15 and 16 are turned into parallel relation, the members 23 and 24 will be likewise turned into parallel relation, as will the members 21 and 22, assuming that the rafter sections 19 and 20 are
- 35 40 swung down into parallel relation. Under these circumstances, this section of the roof supporting structure may be folded into the case and the other half section also folded into the case on top of the first named section, as illustrated in Figure 9.
- 45 The members 21 and 22 of the two sections of the roof meet at the ridge of the roof and these sections are held together by latches of any suitable character. I have illustrated one of the members 21 and 22 as being provided with a plurality of outwardly projecting tongues 26 and the other members 21 and 22 as being provided with clips 27 in which these tongues are inserted.
- 50 55 The stringers are held from spreading away from the peak support formed by the two sets of members 21 and 22 by means of wire ties 28 and 29 which are connected to the stringers and at their inner ends are formed with coacting hooks and eyes, as at 30 (see Figure 3). Any number of these ties may be used along the length of the stringers and when it is desired to fold up the two halves of the roof supporting structure these
- 60 65 ties are released from each other and folded

back upon the stringers, but when the stringers are unfolded so as to support the tent these ties are engaged with each other, as illustrated in Figure 3.

Preferably the inner ends of both stringers formed of the members 15 and 16 are supported by brackets 30, which brackets are hinged at 31 to the side wall of the box or casing so that the brackets swing inward with the stringers. It will be noted from Figure 4 that the section 21 on one-half of the roof supporting structure is longer than the corresponding section of the other half of the roof supporting structure and that the section 22 on the other half is longer than the same section on the first named half so that these sections when brought together break joints, as illustrated in Figure 4.

For the purpose of supporting the stringers and the members 23 and 24, I provide a plurality of extensible supports each formed of two sections 32 and 33, these two sections overlapping each other and having sliding engagement upon each other by means of the clips 34 which are attached to one section and embrace the other section. These members 32 and 33 are held in adjusted position by a lever clamp 35 which, when turned down, jams the two sections 32 and 33 against each other and holds the sections in their adjusted positions. These sections at their upper ends are formed to engage with the members 15 and 16 and 23 and 24 on the sides and ends of the supporting structure. These adjustable supports formed of the sections 32 and 33 are adapted to be disposed beneath the closed top in the section X, as shown in Figure 1.

The section Y is intended to contain a cabinet likewise formed in two sections hinged to the end walls of the case, a table top, legs therefor, and a foldable cot. To this end there is hinged to the end walls of the lower section Y of the case the two cabinet sections 36 and 37 (see Figure 15). Both these sections are alike. Each extends half the length of the section Y and each has a depth less than the depth of the section Y so that there is a space between the backs of the cabinet sections 36 and 37 and the back of the case when the cabinet sections are turned into closed position. The front of each cabinet section is formed with a plurality of shelves 38 and compartments within which food, clothing or any other desired material may be placed. These cabinet sections are hinged at 39 to the end walls of the section Y of the case so as to swing outward entirely out of the way and disclose the space behind these cabinet sections, a cot being adapted to be disposed behind these cabinet sections, as will be later explained.

The end walls of the section Y are formed from a point adjacent the bottom of the section about half way of the height of the

section each with a vertically extending slot 40 and the upper end of this slot being extended rearward and downward, as at 41. A table top 42 is provided with trunnions 43 which operate within these slots 40. These trunnions 43 are disposed at the inner edge of the table top. Therefore, this table top may be turned to a position extending entirely across the front of section Y, as shown in Figure 14, or brought up to the top of the slots and disengaged through openings 44 or carried back into the portions 41 of the slots and thus the inner edge of the table top will be hingedly supported.

For supporting the outer margin of the table top, I provide the hinged legs 45 hinged to the table top in any suitable manner and connected by a longitudinally extending rod 46 and braces 47. When the table top is shifted upward and its trunnions engage with the extensions 41 of the slots 40, the table top may be swung into a horizontal position and the legs will be depressed and rest upon the ground, it being understood that the bottom of the section Y of the case rests not upon the ground but upon an elevated support as, for instance, the running board of the automobile or the rear portion of the frame of the automobile where trunks are supported or carried. The lower ends of the end walls of the section Y of the box are each formed with a slot 48 which extends upward and forward at a slight angle and then extends straight downward. This is for supporting a cot, as will now be described.

The cot structure is also foldable and comprises the end members 49 and 50, these end members constituting two sections hinged together at 51, the hinge being such that the sections 49 may be folded over upon the sections 50. A middle supporting member is also formed of the sections 52 and 53 hinged at 54 and to the sections 50 are pivoted the legs 55 and to the section 52 the legs 56, the legs being disposed one on each side of the section 52. Rails 57 connect the legs 55 with the legs 56. Thus each section has a leg 56, a leg 55 and a rail 57. Pivoted to the forward ends of the sections 49 are the legs 58 and to the forward end of the rail 53 are the legs 59, these legs being connected by transverse rails 60. An extension frame 61 is also hingedly connected to the forward ends of the members 49 and 53 and is supported by braces 62 hingedly connected to the extension member and adapted to engage the legs 58. This extension member 61 is adapted to be folded over upon the face of the front section of the cot. This cot is intended to be covered with canvas and to provide room for two people. The canvas is designated 63 and may be attached in any suitable manner to the frame of the cot.

The inner ends of the members 50 and 52

are connected by means of a rail 64, to which the canvas is attached, and this rail 64 is disposed adjacent the inner ends of the members 50, the extremities of the members 50 being provided with outwardly projecting trunnions 65 engageable in the slots 48. Thus after the bed is folded up it may be shifted to the rear of the case section Y to permit the closing of the cabinet doors.

Obviously, when the cot is in use the table must be put out of the way and, therefore, I provide the entrance openings 44 to the slots 41 which permit the table trunnions 43 to be removed from their engagement with the slots 40 and 41 and to be engaged with downwardly and rearwardly extending slots 66 and the table disposed in the upper box section X, wherein it fits, thus permitting the cot to be utilized. The cot, when folded up, occupies the rear portion of the section Y and, therefore, as space is left beneath the swinging cabinets 36 which may be utilized for storing clothing or for any other purpose as, for instance, the storing of folding camp chairs or stools. While I have illustrated a cot formed of canvas, springs might be used and a folding cot not connected to the casing might be disposed in this space.

The canvas covering is also formed in sections and is intended to be permanently attached to the outside faces of the side walls and the top wall of the upper section of the case preferably by means of the snap fastener members 12 and 13 previously referred to. The canvas is cut to form two sections A and B, these sections being substantially alike. The section B is formed to provide one-half of the roof d and to extend down at the side of the tent structure, as at b, and the forward edge of this portion b is provided with snap fasteners 67. Attached to the forward end of the roof section d is the flap e which extends downward and covers one-half of the forward end of the tent. This flap e is provided on one margin with snap fastener members coacting with the snap fastener members 67 on the portion c' and fits over this portion c'. The corresponding roof section d' of the section A of the tent also has a flap e' extending downward but this flap laps beneath the flap e end is engaged therewith by snap fastener members 67. The roof portion d' extends beyond the ridge of the roof and beneath the upper margin of the portion d and these two sections are connected by snap fastener members 68. The rear end of each section b and b' is laterally extended inward toward the casing and then engaged at its margin with the case by the snap fastener members previously described, and the same is true of the section A. The rear portion of the roof portcouns d and d' is extended downward, as at f, and then extended along the

top wall and engaged with the snap fastener members 13. The same is true of the rear end of the roof portion d'.

It will be noticed that the canvas is not fastened to the top at all but buttons on the case up each side and over the case. It also buttons up at the corners, and up the center front, and the roof pieces lap each other and button to one side of the ridge of the roof so that there is no chance for rain to get it at this ridge.

To fold up this tent, the tie rods 28 and 29 are unhooked and the ridge pole sections 21 and 22 are pulled apart from each other so as to release the engagement between the clips 27 and the tongues 26. These sections are then allowed to drop down. The canvas is then unbuttoned up the front and across the top and along the ridge and the next step is to unbutton the front corners and fold the front canvas over the stringers, next unbutton the canvas from the case and unbutton the back corners and then fold the canvas from the back over the top and then the side wall over the top, remove the supports for the sections 23 and 25, and let these sections drop parallel to the sections 21 and 22. The sections 15 and 16 and the sections 23, 24, 21 and 22 may be then folded upon each other and the whole supporting structure of the tent is adapted to be folded into the top section of the case. Assuming that the cot has been folded up, the swinging cabinets closed and the table folded up, then the two sections of the case may be folded together and closed and the case is ready for further travel. The reverse steps are carried out when it is desired to unfold the tent and erect the tent supporting structure.

While I have illustrated a construction which I believe to be particularly effective, I do not wish to be limited to the details thereof as these might be varied in many ways without departing from the spirit of the invention.

I claim:—

1. An automobile camping outfit including a box adapted to be carried on an automobile running board and formed of two hingedly connected sections adapted to be turned into superposed vertical relation, a tent supporting structure having foldable members hinged to the end walls of the upper section of the box and foldable thereto, said foldable members supporting transversely extending foldable members hinged to the first named members, and a tent detachably connected to the box and formed to fit over said tent supporting structure.

2. An automobile camping outfit including a box adapted to be carried on an automobile running board and formed of two hingedly connected sections adapted to be turned into superposed vertical relation, a

tent supporting structure including longitudinally extending stringers formed in a plurality of hinged sections, one of the end sections being hinged to the side walls of the box, rafter members formed in sections and hingedly connected to the stringers, longitudinally extending members parallel to the stringers and connected to the ends of the rafter members and formed in a plurality of sections, means for supporting the stringers and said last named members from the ground, and a tent detachably connected to the box and formed to fit over said tent supporting structure.

3. An automobile camping outfit including a box adapted to be carried on an automobile running board and formed of two hingedly connected sections adapted to be turned into superposed vertical relation, a tent supporting structure including longitudinally extending stringers formed in a plurality of hinged sections, one of the end sections being hinged to the side walls of the box, rafter members formed in sections and hingedly connected to the stringers, longitudinally extending members parallel to the stringers and connected to the ends of the rafter members and formed in a plurality of sections, longitudinally adjustable supports adapted to be disposed beneath the stringers and beneath the last named members to support the same, and a tent detachably connected to the box and formed to fit over said tent supporting structure.

4. An automobile camping outfit including a box adapted to be carried on an automobile running board and formed of two hingedly connected sections, a tent supporting structure including a pair of stringers, each formed in two hingedly connected sections, the inner ends of each stringer being hingedly connected to the sides of the box whereby the stringers may be folded up within the box, rafters, each formed of two sections hinged to the stringers and adapted to be turned into an approximately horizontal position or into parallel relation to the stringers, ridge pole members connected to the inner ends of each set of rafters and formed of two hingedly connected sections, means on the ridge pole members for detachably connecting them, eaves members connected to the outer ends of the rafters and each formed of two hingedly connected sections whereby the several members may be folded up and folded within the box section, vertically adjustable supports adapted to be disposed beneath the stringers and the eaves sections, and a tent structure detachably connected to the side and top wall of the box and formed of two sections of canvas detachably engaged with each other.

In testimony whereof I hereunto affix my signature.

FRANK E. ALLEN.
